UNITED STATES PATENT OFFICE

RALPH C. EISEL, OF PITTSBURGH, PENNSYLVANIA, ASSIGNOR TO PITTSBURGH GARTER COMPANY, OF PITTSBURGH, PENNSYLVANIA, A CORPORATION OF PENNSYLVANIA

MAN'S GARTER

Application filed December 12, 1929. Serial No. 413,445.

The object which I have in view is the improvement in the means for attaching to the pad of the garter a stud plate which carries the stud which is engaged by the wire loop 5 of the free end of the leg band.

In the present practice the usual method of attaching the stud plate to the pad is by sewing, the loops of the thread extending through the pad or through the outer member or layer 10 of the material of the pad. This method is unsatisfactory because the metal of the stud plate tends to cut through the stitches and also because the sewing forms a lump or irregularity which is pressed into the leg.

Another method which is in use is the introduction of the base plate of the stud between the pad members, the stud protruding outwardly through a hole in the outer pad member. Here again a lump is formed which is pressed into the leg. There is also a tendency of the base plate to tilt and thus become uncomfortable.

Still another method of attaching the stud plate is to thread through the slot a strip or 25 length of textile material whose ends are sewed to the pad. This method requires the extra material of the textile strip and the additional work of forming the same and installing it in place.

The object which I have in view is the provision of an improved means for attaching the stud plate to the pad, the attachment being such that no additional material is required nor any additional seams or stitching, the seams which are used to sew the pad members together being also used to sew the stud plate to the pad.

In my improved garter the stud plate is 40 secured to and held against the outer face of the pad by means of a tongue of the material of the outer member of the pad which is threaded through the slot in the stud plate and has its end secured to the rear pad member by the same seam or seams of stitching 45 which are employed to sew the pad members together and also secure the end of the leg band to the pad.

In the accompanying drawings, wherein 50 I have illustrated a practical embodiment of

the principles of my invention, Fig. 1 is an elevation of the garter, with the leg band in its closed position as it is when looped about the wearer's calf. The garter shown is for the right leg.

Fig. 2 is an elevation of the front member of the pad, showing the tongue cut therein.

Fig. 3 is a sectional view taken along the line 3—3 in Fig. 1.

Fig. 4 is an elevation of the stud plate.

Referring to the drawings, 1 represents the extensible leg band usually made of elastic webbing and having its one end permanently secured to the pad and its other or free end provided with a wire loop 2 which may be 65 engaged by the stud 3 which is rigid with the stud plate 4. The stud plate 4 is provided with a slotted opening 5 extending transversely of the plate in the rear of the stud.

The pad is composed of the outer or front member 6 and the rear member 7. Either or both of these members may be formed of textile material or leather. The pad members 6 and 7 are assembled and held together by the parallel rows of stitching 8 which run around the edges of the pad and the end of the band 1 is secured to the pad by being inserted between the pad members and being sewn in place by means of the rows of stitching 8. Depending from the pad is the usual 80 hose-engaging means 9.

To attach the stud plate to the pad I cut in the material of the outer pad member 6 a tongue 10, the lines of cut extending inwardly from the edge of the member as shown in Fig. 2. This tongue 10 I thread through the slot 5 in the stud plate 4, and then with the same stitching 8 and the same operation by which the pad members 6 and 7 are sewed together and the end of the band 1 is attached 90 to the pad I sew the free end of the tongue 10 fast in place as shown in Fig. 1, thus employing but one stitching operation to form the pad, to secure the end of the band 1 thereto and to attach the stud plate to the pad. In cutting the tongue 10 in the material of the pad member 6 the upper cut is preferably not extended inwardly quite as far as is the lower cut as is shown in Fig. 2, thus causing the 95 100

stud plate to be tilted slightly as shown in Fig. 1, thus disposing the loop strap 1 in proper manner to comfortably engage the leg above the swell of the calf.

5 The pull of the stud is exerted on the inner end of the tongue so there is no abrasion or wear on the stitching which holds the stud plate in place. The more or less loose engagement of the stud plate by the tongue provides for a freedom of movement of the stud plate, allowing it to swing and thus preventing binding or pinching when the wearer walks or runs.

Again, it is evident that the stud plate is attached in such a manner that no lump or hard surface is formed to press into the leg.

By the use of my invention a saving is accomplished in time and labor in manufacturing the garters, and the completed structure is of improved strength and resistance to wear.

What I desire to claim is:—

1. In a garter, the combination with a pad formed of a plurality of properly shaped textile members sewed together in superimposed relation by stitching adjacent to the edges of the members, a leg-band having its one end permanently attached to the rear edge of the pad, a wire loop on the other end of the leg band, a stud to be engaged by the wire loop and a stud plate upon which said stud is rigidly mounted and which is provided with an opening, and means for securing the stud plate in place against the outer face of the pad comprising a tongue cut from the material of the outer pad member by cuts extending inwardly from the rear edge of the pad and the tongue threaded through the opening in the stud plate, and the outer end of the tongue being stitched to the pad.

2. In a garter, the combination with a pad formed of a plurality of properly shaped textile members sewed together in superimposed relation by stitching adjacent to the edges of the members, a leg-band having its one end permanently attached to the rear edge of the pad, a wire loop on the other end of the leg band, a stud to be engaged by the wire loop and a stud plate upon which said stud is rigidly mounted and which is provided with an opening, and means for securing the stud plate in place against the outer face of the pad comprising a tongue cut from the material of the outer member by cuts extending inwardly from the rear edge of the pad and the tongue threaded through the opening in the stud plate, and the outer end of the tongue being stitched to the pad by the stitching which attached the pad members together.

3. In a garter, the combination with a pad formed of a plurality of properly shaped textile members sewed together in superimposed relation by stitching adjacent to the edges of the members, a leg-band having its one

end permanently attached to the rear edge of the pad, a wire loop on the other end of the leg band, a stud to be engaged by the wire loop and a stud plate upon which said stud is rigidly mounted and which is provided with an opening, and means for securing the stud plate in place against the outer face of the pad comprising a tongue cut from the material of the outer pad member by cuts extending inwardly from the rear edge of the pad and the tongue threaded through the opening in the stud plate, the outer end of the tongue being attached to the pad and the same stitching used to secure the pad members together, securing the outer end of the tongue to the pad and securing the end of the leg band permanently to the rear edge of the pad.

Signed at Pittsburgh, Pa., this 11th day of December, 1929.

RALPH C. EISEL.
